UNITED STATES PATENT OFFICE.

LEWIS G. HOWLETT, OF BAY CITY, MICHIGAN.

WINCH.

1,274,549.

Specification of Letters Patent.

Patented Aug. 6, 1918.

Application filed March 12, 1918. Serial No. 222,015.

To all whom it may concern:
Be it known that I, LEWIS G. HOWLETT, a citizen of the United States, residing at Bay City, in the county of Bay and State 5 of Michigan, have invented certain new and useful Improvements in Winches; and I do hereby declare the following to be a full, clear, and exact description of the invention, such as will enable others skilled in the art 10 to which it appertains to make and use the same.

This invention relates to winches and pertains more particularly to an improved construction in a winch adapted to be used on 15 vehicles such as motor trucks.

The objects of the improvement are to provide a power-transmitting mechanism for a truck winch, adapted to transmit power to the winding drum evenly and without binding or undue friction, even though the frame of the winch and the supports on which the main bearings are mounted become sprung out of alinement from any cause, such as sudden jerks due to slippage 25 of the load, unevenness of the truck frame, or warping or springing of the truck frame.

In winches as ordinarily constructed, with cylindrical bearings and rigid frames, to which the power transmission is secured, a 30 warping or twisting of the winch frame results in binding at the bearings or improper driving contact between the driving worm and the worm wheel of the winch, resulting in unnecessary friction, reduction of power 35 and rapid wearing of the gears.

To overcome this objection and to provide a winch in which considerable springing of the frame and improper alinement of the main bearings may take place without interfering with the efficiency of the transmitting mechanism I have provided the device herein described and claimed and it is this device and the equivalents thereof which constitute my present invention.

45 In the accompanying drawings, Figure 1 is a side view of my improved winch applied to the frame of a motor truck.

Fig. 2 is a part longitudinal section on the line 2—2 of Fig. 1.

50 Fig. 3 is an enlarged transverse section on the line 3—3 of Fig. 2, the shaft and worm wheel being removed, the worm being shown diagrammatically.

As is clearly shown in the drawings, the 55 winch consists in a frame comprising the

pedestals 1 and 2 connected by cross beams or sleepers 3 and carrying the drum-shaft 4, upon which is mounted the drum 5 and a suitable clutch mechanism 6, disengaged from the shaft 4.

As previously stated, my present improvement pertains more particularly to the means for supporting the drum-shaft on the pedestals and the arrangement of the driving worm and worm wheel with relation to the shaft and frame, whereby the proper degree of flexibility is imparted to the driving mechanism to keep the worm and worm wheel in proper relation to each other, even though the frame of the truck and its main 60 bearings become thrown out of alinement.

My improvement comprises a pair of spherical journal boxes 7 and 8, in which the shaft 4 revolves, the boxes being mounted in spherical sockets in the pedestals 1 and 2 respectively, as shown in Fig. 2. One of the journal boxes, as 7, is preferably formed integral with the housing 9 of the worm wheel 10 which wheel is fixed to the shaft 4.

The lower part of the housing 9 is formed 80 with a worm housing 11, in which is mounted the worm 12. The worm is carried by a shaft 13 which is preferably driven by means of a chain 14 and suitable sprockets from the driving or power shaft 15 of the 85 truck.

Since the housing 9 of the worm wheel and the housing 11 of the worm are integral and both are supported by the shaft 4, the 90 housings with their contained worm and worm wheel are capable of moving with the shaft 4 independent of the frame of the winch should the frame become warped or its bearings be thrown out of alinement, that is to say, the proper relative positions of 95 the worm and worm wheel are maintained within the housings 9 and 11 regardless of distortion of the frame of the winch. To permit a proper degree of movement to the housings 9 and 11 with relation to the frame 100 and to prevent too great movement, I provide on the cross beams 3, or on any equivalent part of the frame, stops 16 and 17 adapted to be engaged by the ends of the housing 11, as indicated in Fig. 3. The degree of permissible movement of the 105 housings 11 may be regulated by means of shims 18, or their equivalents.

It is evident that the required degree of movement to produce the necessary flexi- 110

bility or what I term "floating" of the worm and worm gear, is slight, even though the distortion of the frame be considerable.

I have found in practice that the chain 5 drive 14 is capable of sufficient movement to permit the required shifting of the housing 11 and its worm 12.

Although I do not desire to confine myself to the specific construction of the worm 10 mounting in its housing 11, I have shown in Fig. 3 a preferred arrangement of the bearings and thrust mechanism as follows:

One end of the housing 11 is provided with a head 21 carrying a journal bearing 15 22. The opposite head 23 carries a similar journal bearing 24 and a stuffing box and gland 25, to receive the shaft 13. At one end of the worm 12 is a loose washer 26 of brass or anti-friction metal and at the opposite 20 end of the worm is a thrust bearing 27 adapted to take the working thrust of the worm 12. Thus thrust is transmitted through the head 23 to the stop 16 when the winch is under load.

By the means above described I have produced a winch, the power-transmitting gear of which is not subject to distortion when the frame of the winch becomes distorted. Moreover, the efficiency of the power transmission 25 is maintained, even though the frame of the truck becomes sprung, or the

frame of the winch is thrown out of line, either by the sudden slippage of a chain while hoisting the load, or by the sudden application of the brake when a heavy load 35 is being lowered.

Having thus described my invention what I claim and desire to secure by Letters Patent is:

1. In a winch, a frame, journal boxes 40 thereon adapted to slight oscillatory movement, a drum shaft revolubly mounted in said boxes, a worm wheel fixed to said shaft, a worm, a worm housing supported by said shaft and capable of slight oscillatory movement, 45 a stop secured to said frame, and means adapted to rotate said worm.

2. In combination, a winch comprising pedestals, a drum shaft and a worm wheel fixed thereon, spherical journal boxes on 50 said pedestals, a worm wheel housing carried by said drum shaft and capable of slight oscillatory movement, a worm housing integral with said worm wheel housing, a worm revolubly mounted in said worm 55 housing, a thrust bearing carried by said worm housing, a driving shaft, means for revolving said driving shaft, and stationary stops adapted to limit the oscillatory movement of said housings.

In testimony whereof I affix my signature.
LEWIS G. HOWLETT.
